QUICK-ACTING LEVER ACTUATED
PIPE VISE

Leon J. Ferree, Coffeyville, Kans., assignor of
one-half to Melvin J. Huxtable, Kansas City,
Mo.

Application February 21, 1944, Serial No. 523,274

3 Claims (Cl. 81—19)

1

My invention relates to vises, and more particularly to a quick acting pipe vise.

In cutting and threading pipe, particularly on larger jobs, or on jobs in which a large amount of the same size of pipe is used, it is highly desirable to leave the jaws of the vise set in a fixed relative position on the yoke-like member of the vise and the base member, so that the screw-threaded adjusting member does not have to be moved back and forth to release the pipe each time that the vise is opened up to put a new length of pipe into the same or to advance a length of pipe in the same from one position to another for performing cutting or threading operations thereon. The same thing would apply to rod-like members or to other tubular members besides pipe, such as electrical conduit.

It is a particular purpose of my invention to provide a vise in which it is unnecessary to adjust the movable jaw member thereof relative to the yoke-like member after the same has once been adjusted to properly clamp a piece of pipe between the jaws of the vise, as long as the same size pipe, or similar member, circular in cross section, is placed between said jaws. While a member circular in cross section is referred to herein, it is to be understood that any member that can be clamped between the jaws of a pipe vise can constitute the work inserted between the jaws of my improved vise.

It is a particular purpose of my invention to provide a vise in which said above referred to yoke-like member is provided with the usual mounting for a rigid jaw slidably relative to the yoke-like member, and screw-threaded means for adjusting the position of said rigid jaw relative to said yoke-like member, to thus adjust said jaw to proper pipe clamping position, when the yoke-like member and base member carrying the jaws are in proper cooperative relation, which yoke-like member is provided with means for successively bringing the yoke-like member into what is ordinarily referred to as a closed position, or a position adjacent the base member, and locking said yoke-like member to said base member with the jaws in clamping engagement with the work.

It is a further purpose of my invention to provide a vise of the above mentioned character with a lever for performing the operation of closing the vise and clamping the jaws to the work, which also serves as means for successively releasing the jaws from the work and opening the vise so that the work can be removed therefrom. Means is thus provided whereby, with a single

2

movement of the lever referred to, the vise can be quickly adjusted to clamp a piece of work therein and quickly adjusted to remove a piece of work therefrom; in each case by a single swinging movement of the operating lever. This is accomplished by providing a member rotatable about a fixed axis on the yoke-like member, which carries an elongated hook-like member pivotally, the pivot of said elongated hook-like member being mounted eccentrically to the axis of rotation of said rotatable member, and providing means for securing said lever to said rotatable member, so that the same rotate about the axis of said rotatable member as a unit, and further providing means on said lever engaging said hook-like member to swing the same away from the abutment usually provided for such hook-like member on the base member after being unclamped therefrom, and providing means on said yoke-like member engaged by said hook-like member so that further swinging movement thereof by means of said lever will swing the yoke-like member away from the base member, or into an open position, after said hook-like member has been moved out of position adjacent said abutment.

It is a further purpose of my invention to provide means for preventing the hand from slipping on the lever or handle member of the device, and to provide guard means on said handle to prevent pinching of the hand of the operator of the vise between the working parts of the operating means therefor.

Other objects and advantages of my invention will appear as the description of the drawings proceeds. I desire to have it understood, however, that I do not intend to limit myself to the particular details shown or described, except as defined in the claims.

40 In the drawings:

Fig. 1 is a front elevational view of my improved vise.

Fig. 2 is a fragmentary elevational view of the vise as viewed from the rear side thereof, showing the parts in a different position.

Fig. 3 is a fragmentary enlarged sectional view through the rotatable eccentric member through the axis of rotation thereof and adjoining parts, taken substantially on the line 3—3 of Fig. 1.

Fig. 4 is a fragmentary sectional view taken at right angles to Fig. 3, taken substantially on the line 4—4 of Fig. 3.

Fig. 5 is a fragmentary sectional view taken substantially on the line 5—5 of Fig. 1, and

Fig. 6 is a fragmentary top plan view of the

connection between the operating lever, the hook-like member and the yoke-like member of the vise.

Referring in detail to the drawings, my improved vise comprises a base member 6, which is provided with the usual upstanding ears 7, to which one leg 8 of the yoke-like member of the vise is pivotally connected in the usual manner, as by means of a bolt-like member 9. Said base member 6 is also provided with a plane faced abutment 10, provided by the under face of a lateral projection on said base member, this also being common to vises that are provided with hook-like members for detachably securing one of the legs of the yoke-like member to the base member. Said base member is further provided with mounting means 11 for detachably securing a rigid serrated jaw 12 of a substantially V-shaped character, to the base member.

The yoke-like member is of a substantially U-shaped character, having a transversely extending portion 13 and a leg 14 that is substantially parallel to the leg 8. The inner faces of the legs 8 and 14 are provided with guides 15 for a slidably mounted member 16 that detachably carries a serrated jaw 17, such as ordinarily provided on pipe vises, it being common to have the jaw 17 extend between a pair of serrated jaws 12 on the member 11, although the particular arrangement of these jaws to clamp various sizes of pipe therebetween can be varied, the particular jaw structure not being part of my invention. The slidably mounted member 16 is swiveled in the usual manner to a screw-threaded stem member 18, so that said screw-threaded stem can be rotated relative to the slidably member 16, but is held against endwise movement relative to said member 16. Said stem screw-threadedly engages an internally screw-threaded socket member 19, provided in the transverse portion 13 of said yoke-like member in the usual manner, and has a head 20 thereon for receiving the clamping bar, or lever 21, having the usual end enlargements 22 thereon, whereby said stem can be rotated to advance the jaw 17 toward the jaw, or jaws, 12, or move said jaw 17 away from said jaw, or jaws, 12, either to firmly clamp a piece of work, such as the pipe 23 therebetween, when said yoke-like member is fixed relative to the base member, or to release the work.

Said yoke-like member is provided with an enlargement 24 thereon at the outer corner of the junction of the transverse portion 13 and the leg 14, which is provided with a circular bore 25 for rotatably receiving a substantially cylindrical rotatable adjusting member 26. Said rotatable member is straddled by a pair of ears 27, provided on the curved end portion 28 of a lever 29, said curved end portion being shown as being made of a separate piece of material, welded to the tubular member 29 in the drawings, although the members 29 and 28 can be made integral if desired. The ears 27 are fixed to the rotatable member 26 by means of a pair of pins 30 located near the periphery of the rotatable member 26, so that the lever 29 and the rotatable cylindrical member 26 will rotate about the axis of the socket 25 as a unit.

My improved vise is provided with an elongated hook-like member 31 thereon, which has the usual hook portion 32 that is adapted to engage with the flat faced abutment 10 having a substantially flat face 33 thereon engaging said abutment. Said hook-like member is provided with a pair of ears 34 projecting endwise therefrom at the end 75

thereof remote from the hook-like member 32, which ears embrace the ears 27, but are free to slide thereon. The rotatable cylindrical member 26 is provided with an opening 35 therein that is eccentric to the center of said member 25, and which rotatably receives the shank portion 36 of a headed screw-threaded member, the head 37 of which is in engagement with the outer face of one ear 34, and the screw-threaded end of which 10 screw-threadedly engages in an opening 38 in the other ear 34, and is provided with a lock nut 39 thereon so as to lock the parts in adjusted position. The headed screw-threaded member is screw-threaded into such adjusted position that 15 there will be no looseness of the parts, and yet the ears 34 are free to swing relative to the ears 27 to permit easy operation of the device. It will be noted that the arrangement of the parts is such that when the headed screw-threaded pivot member is in position the ears 34 will hold 20 the pins 30 in position to fixedly lock the lever 29 to the rotatable member 26.

The location of the opening 35 is such that when the lever 29 is in the position shown in 25 Fig. 2 the shank 36 of the pivot member for the hook-like member 31 will be swung around to a position on the opposite side of a line, that could be drawn through the axis of rotation of the member 26 and the point of engagement of the hook like member 32 with the abutment 10, to 30 that which the member 36 assumes when in the position shown in Fig. 4, and considerably closer to the leg 14 than in the position shown in Fig. 4, which will release the faces 10 and 33 from clamping 35 engagement with each other, and the jaws 12 and 17 from clamping engagement with the work and permit the swinging of the hook-like member 32 to the position shown in Fig. 2. On the other hand, when the parts are in the position shown 40 in Fig. 4, the member 26 will act as an eccentric clamping means to clamp and lock the faces 10 and 33 together and the jaws 12 and 17 to the work 23.

Means is provided for swinging the hook-like 45 end 32 of the member 31 out of the position in alignment with the abutment 10, said means comprising a finger-like extension 40 on the member 28, which engages an abutment 41 provided on the enlargement 42 on one of the ears 34 provided 50 on said hook-like member 31 for swinging the hook-line member 31 around the member 36 as a pivot to bring it out of aligning position with the abutment 10.

Any suitable means, such as the U-shaped 55 strap-like member 43, may be provided on the leg 14 of the yoke-like member to serve as means engaged by the hook-like member 31 to swing the entire yoke-like member about the pivot 9 into open position, so as to permit ready removal of the work 23 from the vise. Preferably, the lever 29 is provided with a handle portion 44, which is knurled, so as to prevent slipping of the hand on the handle, and is provided with a lateral enlargement 45, which will serve as guard means to 60 prevent the operator's fingers from being pinched between the member 43 and the lever 29, or other parts that are adapted to move in close adjacency to each other.

The hook-like member 31 may be made integral 65 with the member that carries the ears 34, or the member that carries the ears 34 may be made of a separate piece and welded thereto, as shown in the drawings.

In operation, the work, such as the pipe 23, is 70 first placed in position on the base member, after 75

which the yoke-like member of the vise and the hook-like member are moved into the position shown in Fig. 1, by means of the lever 29. Before doing this the jaw 11 is moved to a position where it will not interfere with the clamping action between the parts 10 and 33, and will not be adjusted into position in engagement with the work until after the yoke-like member has been moved into the position shown in Fig. 1. After such position of the yoke-like member has been reached by adjustment of the lever 29, then the lever or handle 21 is rotated to rotate the screw-threaded member 18 in the usual manner to firmly clamp the work between the jaws 12 and 17. After the necessary operations have been performed on the piece of work 23, the vise is released from the work without disturbing the adjustment of the screw-threaded member 18, by moving the lever 29 to first release the hook from the abutment 10 and then swing the yoke-like member into a position to open the vise, to permit removal of the work, through the position shown in Fig. 2. The next piece of work 23 of the same outside diameter of the piece of work previously clamped is then inserted into the vise, being laid upon the jaws provided on the base member 6, and by means of the lever 29 by a single counter-clockwise movement thereof, as viewed in Fig. 1, the yoke-like member is swung into closed position, or toward the base member about the pivot 9, the hook-like member 31 is moved into alignment with the abutment 10, by the action of gravity as the yoke-like member moves into position, and is then moved toward the abutment 10 to firmly clamp the work 23 between the jaws 12 and 17 when the lever 29 reaches substantially the position shown in Fig. 1.

It will thus be seen that both release of the work and opening of the vise is done by a single movement of the lever 29 and the closing of the vise and clamping of the work is done similarly by a single movement of the lever 29 in the opposite direction, making it possible to very rapidly engage and disengage work from the vise, as is highly desirable where a large number of pieces of the same diameter are to be worked on, as in cutting lengths of pipe and threading the same.

What I claim is:

1. In a vise of the character described, a base member having a fixed jaw thereon, a yoke-like member mounted pivotally on said base member, a rigid jaw slidably mounted for adjustment on said yoke-like member, screw-threaded means for adjusting the position of said slidably mounted jaw on said yoke-like member, an abutment on said base member, a hook-like member adapted to engage said abutment, and means for pivotally mounting said hook-like member on said yoke-like member comprising an eccentric mounted on said yoke-like member to rotate about an axis fixed relative to said yoke-like member, means pivotally connecting said hook-like member with said eccentric eccentrically to the axis of rotation of said eccentric, and a lever fixed to said eccentric to rotate the same to clamp said hook against said abutment and a work piece between said jaws, said lever being provided with means for successively releasing said hook-like member from said abutment to release said clamped work piece from said jaws, and swinging said hook-like member away from said abutment by a continuous movement thereof in one direction, said yoke-like member having a U-shaped strap thereon receiving and engaged by said hook-like mem-

ber to swing said yoke-like member about its pivot by means of said lever to open said vise.

2. In a pipe vise, a base member having a fixed rigid pipe gripping jaw therein, a U-shaped yoke-like member having a pair of parallel legs and a transverse connecting portion, said legs being much longer than said connecting portion, said yoke-like member being pivotally mounted on said base member adjacent the end of one of said legs, a rigid pipe gripping jaw slidably mounted on said legs for adjustment toward and away from said fixed jaw, screw-threaded means engaging said transverse portion for adjusting the position of said slidably mounted jaw on said yoke-like member, an abutment on said base member, a cylindrical member rotatably mounted in an opening in said yoke-like member at the junction of the other of said legs and said transverse portion, an elongated hook-like member adapted to engage said abutment, a pivot pin eccentrically pivotally connecting said hook-like member with said cylindrical member, a lever fixed on said cylindrical member to rotate the same about its axis, a stop on said hook-like member, a member on said lever engaging said stop to swing said hook-like member away from said abutment after a predetermined rotation of said cylindrical member, a rigid stop member on said yoke-like member with which said hook-like member engages after a predetermined swinging movement of said hook-like member away from said abutment to positively swing said yoke-like member about its pivotal mounting to a wide open position, and a handle on said lever extending laterally from said yoke-like member during such swinging movement of said hook-like and yoke-like members, said rigid stop member on said yoke-like member having rigid means thereon engaged by said lever after a predetermined swinging movement of said lever in the opposite direction to positively move said yoke-like member from wide open toward closing position by means of said lever.

3. In a pipe vise, a base member having a fixed rigid pipe gripping jaw thereon, a U-shaped yoke-like member having a pair of parallel legs and a transverse connecting portion, said legs being much longer than said connecting portion, said yoke-like member being pivotally mounted on said base member adjacent the end of one of said legs, a rigid pipe gripping jaw slidably mounted on said legs for adjustment toward and away from said fixed jaw, screw-threaded means engaging said transverse portion for adjusting the position of said slidably mounted jaw on said yoke-like member, an abutment on said base member, a cylindrical member rotatably mounted in an opening in said yoke-like member at the junction of the other of said legs and said transverse portion, an elongated hook-like member adapted to engage said abutment, a pivot pin eccentrically pivotally connecting said hook-like member with said cylindrical member, a lever fixed on said cylindrical member to rotate the same about its axis, a stop on said hook-like member, a member on said lever engaging said stop to swing said hook-like member away from said abutment after a predetermined rotation of said cylindrical member, a rigid stop member on one leg of said yoke-like member with which said hook-like member engages after a predetermined swinging movement of said hook-like member away from said abutment to positively swing said yoke-like member about its pivotal mounting to a wide open position, and a handle on said lever extending laterally from said yoke-like member during such swinging

movement of said hook-like and yoke-like members, said rigid stop member on said yoke-like member having rigid means thereon engaged by said lever after a predetermined swinging movement of said lever in the opposite direction to positively move said yoke-like member from wide open toward closing position by means of said lever.
